United States Patent Office

Des. 232,438
Patented Aug. 20, 1974

232,438

DATA TRANSMITTER

William R. Goodale, Claremont, and Ronald E. Loosen,
Malibu, Calif., assignors to MSI Data Corporation,
Costa Mesa, Calif.

Filed Dec. 13, 1972, Ser. No. 314,699

Term of patent 14 years

Int. Cl. D14—02

U.S. Cl. D26—5 C

Fig. 1

Fig. 2

Fig. 4

Fig. 3

Fig. 5

Fig. 6

FIG. 1 is a front perspective view of a data transmitter showing our new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a front elevational view thereof, the bottom being plain and unornamented.

We claim:

The ornamental design for a data transmitter, as shown and described.
